UNITED STATES PATENT OFFICE.

THOMAS P. EDWARDS, OF HAZEL GREEN, WISCONSIN.

PAD-HOLDER.

1,229,730.

Specification of Letters Patent. Patented June 12, 1917.

Application filed March 23, 1916. Serial No. 86,242.

To all whom it may concern:

Be it known that I, THOMAS P. EDWARDS, a citizen of the United States, residing at Hazel Green, in the county of Grant, State 5 of Wisconsin, have invented a new and useful Pad-Holder; and I do hereby declare the following to be a full, clear, and exact description of the invention, such as will enable others skilled in the art to which it 10 appertains to make and use the same.

This invention relates to the art of copy holders and the like, and more especially to improved holder for keeping postoffice money-order pads, bank draft pads, express 15 order pads, counter retail order pads, and calendar pads, and also for holding circular letters and postal cards.

One of the objects of the invention is to provide an improved holder of this kind 20 for keeping such pads on the level with the hand and fore arm, while making out the order, etc., or addressing the letters, post-cards or the like.

Heretofore, such order pads when first 25 being used are higher than the surface of the desk; therefore the hand and forearm are not on the level with the pad.

Hence it is another object of the invention to provide an improved holder having 30 a movable support for the pad, which may be intermittently adjusted as the sheets are diminished and the pad becoming thinner, in order to keep the pad continually on the level with the hand and the forearm.

35 In practical fields the details of construction may necessitate alterations, falling within the scope of what is claimed.

The invention comprises further features and combination of parts, as hereinafter set 40 forth, shown in the drawings and claimed.

In the drawings:

Figure 1 is a view in perspective of the improved pad holder constructed in accordance with the invention.

45 Fig. 2 is a sectional view on line 2—2 of Fig. 1.

Fig. 3 is a plan view of one end of the holder.

Fig. 4 is a sectional view on line 4—4 of 50 Fig. 3.

Fig. 5 is a sectional view on line 5—5 of Fig. 3.

Fig. 6 is a view similar to Fig. 5 showing the clamping support depressed against the 55 action of a spring.

Referring more especially to the drawings,

1 designates the body of the holder, which is hollow, and is constructed of any suitable sheet metal. This body comprises the end pieces 2 and 3, and the bottom and side 60 pieces 4 and 5, and the top piece 6, which is disposed on an inclination from the end piece 2 to the end piece 3. All of said pieces are integrally connected as shown. The top piece 6 is provided with an opening 7, which 65 may be any suitable shape, size or dimension, for instance, just so long as the opening 7 is slightly larger than the size of the pad or the like to be used, and through which opening the pad may be inserted to be supported on 70 the support 8. In other words, when it is desired to arrange the pad, the same is inserted through the opening 7, so as to rest upon the support 8 and then as the pad diminishes the support is adjusted to keep on 75 a level with the upper face of the holder. The body is provided with a partition 11 on its interior, in order to divide off a compartment 12 for the support and the pad thereon. The longitudinal edge portions of 80 the support are provided with downwardly extending flanges 13 and 14. Adjacent the end piece 2 under the part 9 of the top piece a compartment 15 is constructed, by provision of the partition wall 16, which is of 85 the shape clearly shown in Figs. 4, 5 and 6. The flanges 13 and 14 of the clamping support engage the partition walls 11 and 16, which partition wall 16 is provided with a vertical slot 17. Fastened at 18 to the bottom piece of the body is the central part of a bowed leaf spring 19, the free curved ends of which ride in the U-shaped guide member 20, which is secured in any suitable manner to the under face of the support adjacent the 90 flange 14. Pivoted upon the pin 21 in the compartment 15 is a bell crank lever 22, the arm 23 of which is provided with a pin 24, which extends through the slot 17 and is fixed to the flange 14 and the flanges of the 95 U-shaped guide member 20 of the support 8. The arm 25 of the bell crank lever extends through a slot 26 of the part 9 of the top piece 6, and fits loosely in an opening 27 of a slide 28, and the extremity of the arm 25 terminates in a thumb piece 29. Formed in any suitable manner upon the part 9 of the top piece is an arched housing 30 having the guide ribs 31 and 32, between which and the part 9 of the top piece 6 the side portions 33 100 of the slide engage, to guide the slide in its movement. The upper face of the slide 28 105 110

near the center is an inclined cam 35, with which the thumb screw 36 (which is threaded through the upper wall of the housing 30) engages, to hold the slide in different positions. A pad may be inserted through the opening 7, subsequently to having moved the bell crank lever 22, so as to throw the arm 23 downwardly, thereby moving the support downwardly, and holding the same in its downward position by tightening up on the thumb screw 36. As the thumb screw 36 is unscrewed, the support gradually moves upward, the pad protruding through the opening in the holder. Therefore as the pad diminishes in thickness, it is held substantially flush with the upper surface of the holder. When the support is in this position, for instance as shown in Fig. 6, it being supposed that a pad is on the support, the slide has been moved toward the left in Fig. 6. Therefore in this case the shank of the thumb screw may be brought in contact with the inclined cam; thereby holding the clamping support in such position. It is to be noted, however, that when the sheets of the pad diminish the thumb screw may be intermittently unscrewed, thereby allowing the slide to intermittently move toward the right in Fig. 6, in which case, under tension of the leaf spring 19, the support will gradually and intermittently be raised. However, the thumb screw may be dispensed with, or in other words, need not be operated, in which case the support will automatically rise as the pad decreases in thickness incident to the sheets thereof being utilized, thereby always maintaining the pad on the level with the hand and the forearm.

When the thumb screw is dispensed with, it is understood that the pad to be used shall be of the width of the platform 8. The edges of the pad will then abut the edges of the parts 6 and 9 which project over the platform 8. While the face of the pad will then not be exactly level with 6, it will be near enough for all practical purposes. The spring tensioning means will always keep the pad abutting these projections as fast as its individual sheets are removed. Of course it is understood that the pad will have to be bent slightly when it is first inserted upon the platform 8 and in removing individual sheets it will be necessary to

withdraw them from underneath the projections referred to. 55

The invention having been set forth, what is claimed as new and useful is:

1. In a pad holder, the combination of a hollow body having an opening in its upper wall and a compartment below the opening, of a pad support in said compartment to support the pad through and in registration with the opening, spring tensioning means to cause the support to rise as the pad diminishes in thickness; said spring tensioning means including a U-shaped guide on the under face of the support, in which the free ends of the spring tensioning means are guided, a bell crank lever pivotally mounted in one end of the body and having one arm pivotally connected to the support, a housing on the top of the body having guides, a slide mounted in said guides and having a slot connection with the other arm of said lever, and provided with an inclined cam, and a thumb screw engaging said cam and designed to be intermittently unscrewed, to permit the action of the spring means to elevate the clamping support as the pad diminishes in thickness. 75

2. In a pad holder, the combination of a hollow body having an opening in its upper wall and a compartment below the opening, of a pad support in said compartment to support the pad through and in registration with the opening, means to cause the support to rise as the pad diminishes in thickness; a bell crank lever pivotally mounted in one end of the body and having one arm pivotally connected to the support, a housing on the top of the body having guides, a slide mounted in said guides and having a slot connection with the other arm of said lever, and provided with an inclined cam, and a thumb screw engaging said cam and designed to be intermittently unscrewed, to permit the action of the raising means to elevate the support as the pad diminishes in thickness. 90

In testimony whereof I have signed my name to this specification in the presence of two subscribing witnesses. 100
